APPARATUS FOR THE DISTILLATION OF
HIGH-BOILING LIQUIDSHeinrich Koppers, Essen, Germany, assignor, by
mesne assignments, to Koppers Company,
Pittsburgh, Pa., a corporation of DelawareApplication February 13, 1939, Serial No. 256,077
In Germany February 15, 1938

2 Claims. (Cl. 202—215)

The invention relates to the distillation of high-boiling substances such as coal tar pitch.

High boiling substances as for instance bituminous coal tar pitch, residues of mineral oil treatment, or residues of coal hydrogenation, are distilled in order to produce valuable oils, or a solid residue such as pitch coke. The high boiling substances of the kind mentioned show a tendency to decompose during the distillation and form solid matters. Therefore it is disadvantageous to treat them in distilling vessels usual for distilling low boiling substances, such vessels being normally heated up from outside. Ceramic chambers are out of the question in this connection as it is to be feared that the distillation products are unnecessarily overheated. Furthermore, ceramic chambers easily become very leaky. At a high temperature the pitch and similar matters become as fluid as water. If the liquid pitch enters the brick joints it carbonizes there, undergoing expansion while doing so and destroys the chamber walls, which are built up of single bricks.

I have found that the distillation of pitch may be effected by passing hot, preferably non-oxidizing gases through the mass during the distillation. The distillates separate very easily from the vapours or gases later when cooling down. On the other hand the hot gases are cooled-down in passing through the pitch and thus the distilling products are protected against being overheated.

Now, according to my invention, an apparatus for the distillation of pitch and similar matters is provided which is of such a design that combustion products of high temperature are driven through the mass, the apparatus for the distillation comprising substantially two parts, the upper part of which, together with a dip pipe, being designed so as to be lifted, after loosening the flanges serving for the connection with the combustion chamber and gas collecting main respectively. If one distils until a solid residue is obtained, this residue may be discharged from the container by a suitable grab.

The distilling vessel may consist of steel and is installed in such a way that the bottom and the sides can be heated up. This heating from outside is applied until a solid residue is obtained and the residue (coke) loosens itself from the walls of the vessel. At temperatures below dull red heat the mass sticks to the metal wall; at temperatures slightly above dull red heat, however, it loosens itself and becomes free so that the solid mass may be discharged by

means of a grab or the like. The lid of the vessel is strongly lined with refractory material for the purpose of insulating it. The rim of the lid extends into a collar of the lower part of the vessel so that a water seal or other effective gas seal means may be provided.

If a so-called hard pitch is intended to be produced from soft pitch, the distillation is interrupted when the desired degree of hardness is arrived at in heating the residue. The mass is then discharged and new material is filled into the vessel. In this case the heating is effected mainly by means of hot gases which are passed through the liquid distillation material.

15 If on the other hand the distillation is to be carried forward until coke is formed the heating is effected as from the outside as well as by passing hot gases inside. After the mass has been evaporated to dryness the passing of hot 20 combustion gases through the interior of the vessel is stopped and the residue is directly cooled in the vessel by spraying water there-over. Then the lid of the vessel is lifted and the vessel is emptied by means of a grab. The 25 dip pipe may be provided with hooks protruding from the side of same and in this case the solid matter formed thus may be easily discharged from the vessel by lifting the dip pipe from which the coke may be removed outside the apparatus.

If pitch coke is to be produced from bituminous coal tar for use for electrodes one may apply various methods.

One may distill the tar in the vessel, for instance, until a hard pitch with a softening point of about 150° C. is formed. This hard pitch then may be charged in a liquid state into a hot coke oven. However, it is also possible to distill in the vessel until a hard pitch with a softening point of about 200 to 220° C. is recovered. Then this material is solidified by running over a suitable cooler such as a cooling conveyor. The cold solid material then may be charged into a coke oven in the manner well known in coke oven practice. In the coke oven the material becomes fluid again and carbonizes and a coke cake is finally formed which may be pushed out in the usual manner.

If the material is distilled in the apparatus 50 designed according to the invention until carbonization to coke takes place in the vessel, it is not possible to drive out volatile matters from the product later in a horizontal chamber oven. In this case the material which has been discharged by the grab has to be crushed and then

degassed, preferably in a continuously operated vertical chamber which is heated up from outside like a vertical chamber or retort oven used in gas works.

The distillation by hot gases with direct contact of the hot gases with the distilling material has the great advantage that the distilling products are protected against undue decomposition. A further advantage consists in the fact that the heating of the vessel from outside need not take place as long as liquid products exist in the distilling vessel. The outer heating is only used if one wants to loosen the solid product from the metal walls of the vessel. According to my experience, difficulties occur only if the vessel is heated from outside, as deposits are formed during the distillation of the liquid matter on the walls, which prevent the heat from being transmitted into the charge; thus the vessel walls may be overheated and be destroyed.

With the above and other objects and features of my present invention in view I shall now describe a preferred embodiment thereof on the lines of the accompanying drawing which shows a vertical cross section of the apparatus designed according to the invention.

The distilling vessel is marked 1. It consists preferably of steel and has the form of a bucket open at the top. The vessel 1 tapers towards its bottom in order to facilitate discharging.

The distilling vessel 1 is surrounded by refractory brick work 2. Below the vessel a heating flue 3 is provided. Within the range of the side walls of the vessel the heating flues 4 are installed. The brickwork 2 is held together by an anchorage 5.

At the upper rim of the vessel 1 a water seal 6 is provided into which extends the rim 7 of the vessel lid 8. The vessel lid 8 is lined with a suitable heat insulating material.

On the outside of the lid 8 ears 10 are provided in which hooks 11 of a travelling crane 12 may engage. By means of this crane the lid of the vessel lid 8 may be lifted.

In the center of the vessel lid 8 an opening is arranged through which a brick-lined pipe 13 extends. The pipe 13 dips into the material to be treated in the vessel 1 (for instance bituminous coal tar pitch). From the dip pipe 13 a pipe 14 which is also brick-lined leads over a flange connection 16 fitted with a compensation installation 15 to a waste gas pipe 17 of a combustion apparatus 18 preferably consisting of a chamber built in refractory material. By means of a blower 21 air and combustion gas is introduced under pressure through pipe lines 19 and 20 into the combustion apparatus 18. The media burn in chamber 18 and pass through the brick lined pipes 14 and 17 into the dip pipe 13. From there they pass through the material to be treated inside the distilling vessel.

During the passage through the distilling material the hot gasses give-off their heat. The cooled down gases together with the distillation vapours escape through the off-take 22 extending from the vessel lid 8. The vapours and gases are drawn off to a cooler connected with a suitable container for the condensate.

The heating flues 3 and 4 are equipped with suitable burners, which are not shown on the drawing for simplicity's sake. The heating flues are preferably used in order to vaporize the volatile content of the vessel until coke is formed.

For instance the process may be carried out in the following manner. The content of the vessel is at first mainly heated up by hot gases coming from the combustion chamber 18 and

5 the heating by the heating flues 3 and 4 only starts when the vessel content is about to solidify. As soon as the content has become solid the heating by means of the gases from the combustion chamber 18 may be stopped or reduced.

10 The heating by means of the flues 3 and 4 is continued for some time until the solidified charge contracts and leaves the metal wall of the vessel 1. This generally takes place when the metal body of the vessel is heated up to dull red heat.

15 After the distilling process is finished the residue, if it is still liquid, may be discharged by means of a siphon or in any other suitable manner. When the vessel content is solid the vessel lid 8 is lifted by means of the crane 12. The hooks 23 provided on the dip-pipe 13 take the solid residue with them. The dip pipe 13 and the hooks 23 can then be freed from the coke by knocking the coke off, or by another 20 suitable method.

25 In order to disconnect the pipe 14, the compensator 15 is slightly compressed by means of a lever 24, or in another way, so that the flanges 16 may move away from one another so far that the pipe 14 is clear off the pipe 17. In order to connect the pipes 14 and 17 again in a gas-tight manner the compensator is brought again in the initial position and the flange connection is closed.

30 35 In a similar way a flange connection is provided at 25 for the pipe 22 of the vessel lid 8.

The crane 12 travels on the framework 26. Several distilling vessels are suitably arranged together so that one single crane 12 may be used for operating each of several apparatus in a battery.

40 45 From pipe 17 branches-off an off-take 27 which is connected to the open air and can be shut off therefrom. Through this pipe 27 combustion gases from chamber 18 may be removed if necessary and when gases are not to be passed through dip pipe 13.

50 55 As may be seen from the above, the hot gases from the combustion chamber 18 are led under increased pressure into the liquid which is contained in the vessel 1. Additional means may be provided to maintain an increased pressure inside the combustion apparatus during the distillation, and for instance, the free section of the pipes connecting the combustion chamber with the distilling apparatus may be varied. This is of advantage as the combustion is complete in the chamber 18 owing to the increased pressure and therefore little carbon monoxide is contained in the hot gases. In consequence the material in the distilling vessel is prevented from being oxidized. It is also possible to connect a vacuum pump to the off-take 22 of the vessel lid 8, or to the condensating device which 60 65 is connected with the lid 8, in order to maintain a reduced pressure in the vessel 1, which allows a distillation of the tarry constituents without decomposition. In this case it is possible to suck the gases from the combustion chamber 18 through the material in the vessel 1.

70 75 The sealing device 6, 7 is suitably filled continuously with water, or another suitable sealing liquor, so that a vaporisation does not take place in the sealing device. Instead of a water seal the connection between the vessel 1 and the

lid 8 can be sealed by means of an asbestos cord impregnated with tar, or in another suitable way.

I have now described my present invention on the lines of a preferred embodiment thereof but my invention is not limited in all its aspects to the mode of carrying it out as described and shown, since the invention may be variously embodied within the scope of the following claims.

I claim:

1. Apparatus for the distillation of high boiling substances such as coal tar pitch, residues of mineral oil treatment or residues of the coal hydrogenation and the like, by means of hot gases passed through the material to be treated comprising a bucket like vessel surrounded by refractory material and open at the top, means for heating said vessel from outside, a separately removable cover adapted to close said vessel, said cover having a pipe like projection on its lower side, said pipe like projection being open

at its lower end and being designed so as to pass hot gases through the material to be treated in said vessel, said pipe like projection being connected on the upper side of the cover with 5 means arranged outside said vessel and adapted to produce hot gases, said cover further being provided with an outlet adapted to draw-off distillation products such as gases and vapours out of said vessel and means for moving hot 10 gases through said vessel connected to the hot gas producing means, the pipe like projection arranged on the lower side of the cover being provided with hook-like extensions protruding sideways to extract coke when the cover and pipe like projection are withdrawn from the vessel.

2. Apparatus as claimed in claim 1 wherein 15 between the distilling vessel and the removable cover means are provided for ensuring a gas-tight connection therebetween.
